DESIGN FOR AN ELECTRIC HEATER

John Ernest Smith, Plainfield, N. J.

Application May 24, 1945, Serial No. 119,708

Term of patent 14 years

(Cl. D81—10)

To all whom it may concern:

Be it known that I, John Ernest Smith, a citizen of the United States, residing at Plainfield, in the county of Union and State of New Jersey, have invented a new, original, and ornamental Design for an Electric Heater, of which the following is a specification, reference being had to the accompanying drawing, forming part thereof.

Fig. 1 is a perspective view;

Fig. 2 is a side elevation, and

Fig. 3 is an end elevation of the electric heater showing my new design.

I claim:

The ornamental design for an electric heater, as shown.

JOHN ERNEST SMITH.
